ELECTRIC CONNECTOR OR TERMINAL

John J. Jolliffe, Hawthorne, N. J., assignor to
 The Okonite Company, Passaic, N. J., a corporation of New Jersey

Application April 25, 1936, Serial No. 76,328

1 Claim. (Cl. 173—322)

This invention relates to improvements in electrical connectors, and is particularly directed to attachment plugs for various electrical devices such as electric irons, toasters and the like.

5 In such devices, as heretofore constructed, the electric cord is subject to a great deal of twisting at the plug, and also to a combination of flexing and tension forces. For example, with cords and plugs for electric irons, there is a short quick 10 bending action of the cord without a great deal of twisting, when the cord is new, but after a few hours of service there is a direct twisting of the cord. This twisting apparently builds up until it finally becomes a force of considerable magnitude 15 and the cord seems to retain this twist until it is disassembled from the appliance. The next time the cord is used this twisting reoccurs. Apparently the twisting action is always in the same direction and at the same rate. Oftentimes the 20 cord is subjected to sufficient tension to pull the plug from its receptacle; this of course places a severe strain on the cord and tends to pull the conductors free from their terminals.

The construction of the device of the present 25 application is such as to overcome these defects or to eliminate their detrimental effect on the device as a whole. For example, my device is so constructed that tension on the cord in a direction to pull the attachment plug out of its receptacle is taken up and absorbed by a spring, one 30 end of which is attached to the plug and the other to the cord. Thus no strain is brought on the cord conductors at their point of attachment to the plug terminals. The twisting of the cord 35 above referred to is resisted by this same spring so that there can be, in ordinary usage, no twisting of the conductors at the point of attachment to the plug terminals.

I might say that by actual comparative tests 40 my device has withstood twenty-five times the twisting that the prior type of cord and plug will withstand.

In the accompanying drawing wherein I have 45 illustrated one embodiment of my invention:

Fig. 1 is a sectional view of my improved attachment plug with the electric cord in place; and

Fig. 2 is a sectional view on line 2—2 of Fig. 1.

Referring to the drawing in detail, 1 designates a plug made up of sections 2 and 3 of moulded insulating material secured to each other in any suitable manner and provided internally with split female terminal members 4 and 5.

6 designates an electric cord, the ends of the conductors 7 of which are connected to the terminal members 4 and 5 by means of screws 8. Surrounding the cord 6 is a spring member 9 the end of which extends into the top of the connector 1 and is held against turning therein by making the end of the spring out-of-round in cross section and recessing the plug to conform with this end of the spring, or in any other suitable fashion.

The outer end of this spring is moulded or otherwise rigidly attached to the cord 6 as shown at 10.

It will be appreciated from the foregoing description that by anchoring the spring 9 at one 20 end to the plug 1 and at its other end to the cord 6, the twisting point of the cord has been moved outside the connector entirely and to a point remote from the connection of the conductors 7 of the cord to the terminals 4 and 5. Inasmuch 25 as twisting of the cord is no longer localized within the plug, rupturing of the cord is reduced to a minimum.

It is to be understood that various changes and modifications may be made in the structure illustrated without departing from the spirit and scope of my invention.

What I claim is:

An electric connector comprising a pair of moulded sections of insulating material, a coil 35 spring one end of which is received between said sections, the said end of the spring being so formed as to be held between said sections against twisting therein, an electric cord extending through said spring and into said moulded sections, terminals within said moulded sections to which the cord conductors are connected, and a member rigidly attached to the end of said spring remote from the said moulded sections, said member being moulded to said cord whereby to prevent twisting of the cord relative to said spring and sections.

JOHN J. JOLLIFFE.
